HIGH-SPEED COUNTER

Maynard C. Yeasting, Elmore, Ohio, assignor to
 Toledo Scale Company, Toledo, Ohio, a corporation of New Jersey

Application December 10, 1946, Serial No. 715,232

4 Claims. (Cl. 235—136)

1

This invention relates to counting mechanisms and in particular to a counter that may operate in either a forward or a reverse direction at extremely high speeds.

Counting mechanisms other than the multiple dial geared counters, such as are used on watt-hour meters, watermeters, and similar instruments, usually employ intermittent motion transmitting means between the various indicia bearing members such that each of the indicia bearing members is stationary except when the indication of the next lower member is changing from 9 to 0 or 0 to 9. The rapid acceleration and deceleration of the intermittently moved indicia bearing members limits the speed at which such counting mechanisms may be operated.

The principal object of this invention is to provide a counter or counting mechanism that may be operated at extremely high speeds and which gives an indication similar to an intermittently operated counting mechanism.

Another object of the invention is to provide a counting mechanism in which a nonrotating gear is oscillated about its axis to provide intermittent motion of a higher order indicia bearing member of the counter.

Another object is to oscillate a nonrotating gear of a planetary gear transmission by means of resilient members that permit the oscillated gear to depart from its prescribed oscillatory motion when such oscillatory motion produces high inertia forces.

More specific objects and advantages are apparent from the following description in which reference is made to the accompanying drawings.

The invention consists in a counting mechanism in which a lower order indicia bearing member is connected to a higher order indicia bearing member by means of a nonrotating gear that is carried on an eccentric portion of the lower order member and engages the higher order member and in which the gear is oscillated by resilient means that also engage a cam on the lower order indicia bearing member. This particular arrangement affords great simplicity in the construction of the counter, provides step by step indication on the higher order indicia bearing members, and, because of the resilience of the gear oscillating means, permits the counter to be operated at extremely high speeds.

A counter embodying the invention is illustrated in the accompanying drawings.

In the drawings:

Figure I is a perspective view, with parts broken

2

away, showing the general assembly of the improved counter.

Figure II is a vertical section taken through the axis of the improved counter.

Figure III is a vertical transverse section taken along the line III—III of Figure II.

Figure IV is a detail elevation taken along the line IV—IV of Figure II.

Figure V is a fragmentary section taken along the line V—V of Figure III.

These specific figures and the accompanying description are intended merely to illustrate the invention but not to impose limitations on the claims.

15 The improved counter as shown in Figure I includes a plurality of indicia bearing drums 1, 2, 3 and 4 enclosed within a cover 5. The front of the cover 5 is provided with a window 6 through which indicia on the drums may be observed.

20 Referring to Figure II the operating mechanism of the improved counter is mounted between end plates 7 and 8. An input shaft 9 journaled in a bearing 10 in the end plate 7 is connected to a device whose revolutions are to be counted. The shaft 9 carries the first or lowest order indicia bearing drum 1, which consists of a disk-like portion 11 on whose outer rim the indicia bearing surface is mounted. The disk 11 is staked onto the end of a hub 12 that includes a cam 13, a concentric spacing portion 14 and an eccentric 15. The hub 12 is pinned to the shaft 9 and, furthermore, is rotatably journaled on a stationary axle 16 mounted in the end plate 8 in axial alignment with the input shaft 9.

35 The next higher order indicia bearing drums 2 and 3 are similarly constructed, each consisting of a hub 17 loosely journaled on the stationary shaft 16 and having mounted thereon a disk 18, a cam 19, a spacer 20 and an eccentric 21. The highest order drum 4 consists of a simple hub 22 that carries a disk 23 to which the indicia bearing surface of the drum 4 is attached. The disks 18 of the intermediate indicia bearing drums 2 and 3 and the disk 23 of the highest order indicia bearing drum 4 are each provided with a series of ten pins or teeth 24 that are equally spaced near the periphery of the disk and extend toward the next lower order drum. The pins or teeth 24, in effect, form a ten-toothed internal gear. Nine-toothed gears 25 are carried on the eccentric portions of the hubs of each of the indicia bearing drums and are of a size such that they engage the teeth 24.

40 If one of the nine-toothed gears 25 is prevented from rotating as the eccentric hub is

55

turned it describes a planetary motion and advances the next higher indicia bearing drum one-tenth of a revolution for each revolution of the hub. Thus if all of the gears 25 are held from rotation, the drum 2 will advance one-tenth of a revolution for each complete revolution of the first drum 1, while the third or hundreds indicia bearing drum advances one-tenth of a revolution for each complete revolution of the second drum. If the gears 25 are restrained against all rotation they execute precisely planetary motions and the lower speed member—the higher indicia bearing member—is driven with continuous uniform motion. If the gear 25 is restrained so that one of its teeth moves along a radial line as the eccentric hub is turned the gear 25 executes a combined planetary and rotary oscillatory movement such that the velocity of the driven drum continuously varies from 0 to $\frac{1}{5}$ the rotary velocity of the next lower indicia bearing drum.

It is desirable that the velocity of a higher order indicia bearing drum be zero while the lower indicia bearing drum exhibits the indicia from 1 through 9 and that the two drums rotate substantially in unison for one-tenth of a revolution as the lower indicia bearing drum goes from 9 to 0. This effect may be produced by oscillating the gears 25 in a predetermined relationship with the rotation of the lower order indicia bearing drums.

The gears 25 each have a slot 26 in which the end of a formed steel spring 27 is engaged. The springs 27, which are anchored to a rectangular bar 28 that spans the space between the end plates 7 and 8, urge the gears 25 counterclockwise as viewed in Figure IV. The slots 26 are long enough so that the gears 25 may execute their planetary motions without deflecting the ends of the springs 27 radially.

Heavier springs 29 also secured to the cross-bar 28 carry on their free ends rollers 30 that engage the cams 13 and 19. The springs 29 are each provided with a U-shaped clip 31 that straddles the adjacent spring 27. The springs 29 are formed so that they tend to force the rollers 30 against the cams with about the same force that the springs 27 push against the bottoms of the clips 31.

The contour of the cams 13 and 19 are the same and are of a shape such that the spring 27 oscillates the gear 25 with a motion that tends to cancel any transmission of motion from a lower order drum to a higher order drum during the time that the roller 30 cooperates with the longer portion 32 of the cam. During the time that the roller 30 engages a shorter rising portion 33 of the cam the oscillation imparted to the gear is such that the higher order indicia bearing member is advanced one-tenth of a revolution, i. e. is advanced to show the next indicia.

If the device is operating at a relatively slow speed the inertia forces of the higher order indicia bearing members are not sufficient to overcome the force of the springs 27 and 29 so that the gears 25 execute their predetermined motions as determined by the cams and the eccentrics. This prescribed motion of the gears 25 produces intermittent motion of a higher order indicia bearing members that is equivalent to the intermittent motion of an ordinary counter.

If the device is operated at higher speeds the inertia of the higher order indicia bearing members is sufficient so that the springs 27 and 29 are unable to overcome the inertia force whereupon the oscillation of the gear 25 is less than the pre-

scribed amount and if the speed is high enough the gears 25 are not oscillated so that the motion transmitted to the higher order members is substantially uniform. During high speed operation it is immaterial whether the roller 30 follows the cam surface all the way around or not, because these parts are made with very little mass so that at all normal operating speeds the impact force between a roller 30 and the cooperating cam is negligible. Furthermore, the roller 30 may be made of a resilient material, while the cams 12 and 19 are made of steel or other hard material so that no damage to the cam or roller occurs if the roller 30 should bounce on the cam.

15 The improved counter is capable of operation in either direction of rotation at practically unlimited speeds. The fact that the motion of the higher order drums is not intermittent at high operating speeds is immaterial because it is impossible to read the counter during such periods of time. The principal requirement is that the indication shall be instantly available when the counter slows down and that it be able to sustain the forces involved in the high speed operation without being subjected to abnormal wear or failure of parts. In the improved counter the intermittent motion is produced by action against resilient members, which members are designed to limit the maximum force which may be transmitted from one indicia bearing member to another.

20 Various modifications may be made in the details of the improved counter without departing from the spirit and scope of the invention.

Having described the invention, I claim:

35 1. In a device of the class described, in combination, a lower order indicia bearing drum, an eccentric hub rotating with the drum, a gear carried on the eccentric hub, a higher order indicia bearing drum, internal teeth on the high order indicia bearing drum that mesh with the gear, a cam on the lower order drum, and operatively connected springs one engaging the cam and the other the gear for oscillating the gear as the cam rotates.

40 2. In a device of the class described, in combination, a lower order indicia bearing drum, an eccentric hub rotating with the lower order drum, a higher order indicia bearing drum, internal teeth on the higher order drum, a gear that is carried on the eccentric hub and that engages the internal teeth, a cam that rotates with the lower order drum, a resilient cam follower and a spring engaging the gear and the resilient cam follower for oscillating the gear.

45 3. In a device of the class described, in combination, a lower order indicia bearing member, a higher order indicia bearing member having internal teeth, an eccentric hub on the lower order member, a gear carried on the hub, said gear engaging the teeth of the higher order member, a cam on the lower order member, operatively connected springs one engaging the cam the other the gear, said cam and springs serving to oscillate the gear in a direction that prevents motion transmission from the lower order member to the higher order member during a substantial fraction of the time and serving to intermittently advance the higher order member during a short portion of one revolution of the lower order member.

50 60 4. In a device of the class described, in combination, a lower order indicia bearing member, a higher order indicia bearing member having internal teeth, an eccentric portion on the lower order member positioned adjacent the higher order member, a cam surface formed on the lower

65 70 75 order member, a cam surface formed on the lower

order member, a gear journaled on the eccentric portion of the lower order member and engaging the internal teeth of the higher order member, a spring holding a follower against the cam, and a second spring engaging the gear and resiliently pressing against the first spring, whereby the gear is urged into oscillatory motion by a force not exceeding the tension in the springs as the lower order member is rotated.
